UNITED STATES PATENT OFFICE.

HENRY BARNES, OF CLEVELAND, OHIO.

TOOTH-BRUSH.

1,059,426.

Specification of Letters Patent.

Patented Apr. 22, 1913.

Application filed December 23, 1911. Serial No. 867,423.

To all whom it may concern:

Be it known that I, HENRY BARNES, a citizen of the United States, resident of Cleveland, county of Cuyahoga, and State of Ohio, have invented a new and useful Improvement in Tooth-Brushes, of which the following is a specification, the principle of the invention being herein explained and the best mode in which I have contemplated applying that principle, so as to distinguish it from other inventions.

My invention has reference both to a tooth-brush and the method of its use.

The object is the provision of an implement of this specific character which, when given a novel manipulation, will promote to a consummate degree, the precepts of mouth hygiene.

My inventive conception, in so far as I am aware, differs from all previous disclosures, not only in structural detail, but also in the theoretical principle of its use. Consonantly, it establishes novel means for more certainly insuring the dislodgment of all matter, notably deleterious particles of food, from between the teeth. As contra-distinguished therefore from the brushing process quite generally in vogue at present, my conception deals rather with the pushing through and withdrawal of the bristles from the intervening spaces of the particular set of teeth to be cleaned. This may be accomplished in the exemplification which the drawings suggest by rocking or tilting the bristle tips of the brush upon the outer contour of the teeth.

The said invention consists of means which are hereinafter fully described and particularly set forth in the claims.

The annexed drawing and the following description set forth in detail certain means embodying my invention, the disclosed means, however, constituting but one of various mechanical forms in which the principle of the invention may be applied.

In said annexed drawing:—Figure 1 is an elevation of a tooth-brush embodying my invention. Fig. 2 is a section on line II—II of Fig. 1. Fig. 3, is a section on line III—III of Fig. 2. Fig. 4, is a view showing the application of my brush to a typodont of the upper jaw preparatory to cleansing of the teeth and looking up. Fig. 5, is a corresponding view with brush and teeth in different relative positions following the first manipulation. Fig. 6, is a similar view dis-

closing the position occupied by the brush relative to the various teeth upon conclusion of a subsequent manipulation.

The construction consists of a handle A and back member proper a^1 which as joined with angular relation to each other may yet be and preferably are of one piece of material. The back member is of concavo-convex shape and in fact, such that its concave contour substantially corresponds with the outer contour of a normal typodont designated in the drawings as "B." The typodont B shown is that of an adult comprising the sequence from front to rear of two incisors, one canine, two bicuspids and three molars. Embedded in according to the most approved manner, and projecting from the concave surface of the back member, are a plurality of non-contiguous pyramidal bristle clusters a^2 , best seen in Fig. 3. These may be as shown in laterally extending parallel rows, a^3 , a^4 , a^5 and a^6 , a^7 and a^8 of two alined clusters each. The rows are each separately designated in Fig. 2.

When the elongated cluster formation a^2 , best seen by cross section in Fig. 2 is adopted, each such individual cluster should have its cross-section dimension, in the direction of the longitudinal dimension of the back member, uniformly constructed or quite small, in order to facilitate the compressed convergence of all the bristles included in any particular cluster between the teeth in the manner desired, and presently elucidated. As best seen in Fig. 2, the cross section of the pyramidal bristle a^2 is substantially rectangular with one larger dimension for the reason stated. As will be readily understood single elongated clusters might be as satisfactorily arranged parallel with each other or a plurality of comparatively broader and stiffer individual bristles might be laterally alined in substantially parallel rows, each such elongated cluster or individual bristle row, as the case might be to be adapted to slip into the spaces between the teeth.

The rows a^3 , a^4 , a^5 , a^6 , a^7 , and a^8 are differentially spaced from one another in the direction of the longitudinal dimension of said back member depending upon the particular tooth against the opposite sides of which they are intended to rub; thus for example, rows a^8 and a^4 which are nearest the free extremity of the back member, are separated a distance sufficient to span the

molar b , and in like manner, the rows a^4 and a^5 might be spaced an equal distance so as to span the molar b^1 . The rows a^5 and a^6 as well as a^6 and a^7 are in like exemplification separated an equal distance which is, however, less than the distance separating the rows a^4 and a^5 , and only sufficient to span the two approximately equal sized bicuspids b^2 and b^3 . The rows a^7 and 10 a^8 are designed to have an intervening space corresponding, let us say with the average width of the canine b^4 and the incisors b^5 and b^6 . As should be readily apparent, the express purpose in thus spacing the several 15 pyramidal clusters a^2 with definite irregularity longitudinally of the back member a^1 is to make more likely, just as the pyramidal shape does in and of itself, the ready entrance of certain bristles laterally of each 20 individual tooth. The relative spacing of successive longitudinally adjacent clusters, while always in a measure arbitrarily determined, should be such that the greatest number of teeth which can be simultaneously 25 cleansed with convenience, will be treated with nearly uniform thoroughness. A series of shorter bristles a^9 extending a lesser distance from the concave surface of the back member are also provided. 30 These shorter bristles may be arranged in clusters of any specific form and are arranged alternately relative to the longitudinal alinement of the pyramidal bristles a^2 . The spacing of the shorter bristles a^9 35 is merely such that they will engage and hence cleanse the flat surfaces of the teeth inclosed by the pyramidal bristle clusters. While they may be arranged in the parallel rows represented, this order is not essential, 40 provided only that they will initially engage any particular tooth somewhat nearer its middle than its lateral edges. In the case of the wider separation of the pyramidal clusters a^2 required to inclose the molars, a 45 double row of the bristles a^9 may readily be embodied and yet adhere to the spirit of their function.

The manipulation of my tooth brush is 50 as follows: Assuming the tips of the approximately pyramidal clusters a^2 to be in light engagement with the row of teeth, as disclosed in Fig. 4, a tilting or rocking movement is imparted to the handle whereupon the bristles may be first forced through 55 the spaces between the forward teeth as seen in Fig. 5. This movement contrives to loosen if not at once dislodge whatever foreign matter chances to have become seated between these teeth. Thereafter the 60 tilting is set up in the opposite direction and continued alternately back and forth until all the pyramidal clusters a^2 have be-

come wedged in the respective tooth intervening spaces allotted them, as appears in Fig. 6. In this way, the teeth are actually 65 cleansed where decay is most apt to occur, and the desired hygienic results necessarily attained. Practice has furthermore demonstrated that the gums very soon become calloused, consequently concern in respect to 70 their welfare is unwarranted.

Having fully described my invention, what I claim and desire to secure by Letters Patent is:—

1. A tooth-brush comprising the combination with an elongated back member; of non-contiguous laterally elongated bristle clusters differently spaced along the longitudinal dimension of said back member, the cross section of said clusters being uniformly constricted in the direction of the perpendicular to said longitudinal dimension. 75

2. A tooth-brush comprising the combination with a back member; of differing bristle clusters respectively alined in a lateral direction; said alinements being spaced apart with definite irregularity and alternately arranged in the longitudinal direction of said back member. 85

3. A tooth-brush comprising the combination with a concavo-convex back member having a concave contour corresponding with the outer contour of the normal typodont; of bristle clusters projecting from 95 the concave surface thereof, said clusters being arranged in substantially parallel laterally extending rows, alternate rows being spaced with definite irregularity, said alternate rows of clusters being further of substantially rectangular cross section and having a longitudinal dimension corresponding in direction with the lateral dimension of 100 said back member.

4. A tooth-brush comprising the combination of a concavo-convex back member having a concave contour corresponding with the outer contour of a normal typodont, bristle clusters of laterally elongated cross sectional area arranged in laterally extending rows and projecting given distances from the concave surface of said member; other intermediary clusters projecting a lesser distance from said surface and arranged in similarly extending rows, said laterally elongated clusters being non-contiguous and irregularly spaced longitudinally. 110

Signed by me, this 19th day of December, 1911.

HENRY BARNES.
